UNITED STATES PATENT OFFICE.

EDWARD S. AITKEN, OF BRIDGEPORT, CONNECTICUT.

DESIGN FOR A GAME-BOARD.

55,404.

Specification for Design.

Patented June 8, 1920.

Application filed February 17, 1920. Serial No. 359,349. Term of patent 14 years.

To all whom it may concern:

Be it known that I, EDWARD S. AITKEN, a subject of the King of Great Britain, residing at Bridgeport, county of Fairfield, State of Connecticut, have invented a new, original, and ornamental Design for a Game-Board, of which the following is a

In the accompanying drawing the figure is a plan view of a game board, showing my new design.

I claim:

The ornamental design for a game board, as shown.

In testimony whereof I affix my signature.

EDWARD S. AITKEN.
